HOT AIR FURNACE

Filed Sept. 12, 1927

Fig. 4.

BY

James Ephraim Witte

Geo. A. Danner
ATTORNEY.

INVENTOR.

UNITED STATES PATENT OFFICE

JAMES ELIPHAS WITTE, OF NEWPORT, KENTUCKY

HOT AIR FURNACE

Application filed September 12, 1927. Serial No. 218,916.

The invention relates to furnaces particularly, although not exclusively, adapted for heating air for dwellings and the like.

The objects of the invention are to provide simple, durable and economical means adapted to admit supplemental air to the burning gases produced in said furnace, thereby improving the combustion efficiency of the furnace, whereby the production of smoke is eliminated or reduced; and to provide means whereby any of the various grades of fuel and bituminous coal may be efficiently burned in said furnace.

Other objects of the invention will be apparent by reference to the hereinafter description.

The invention consists in the combination and arrangement of the various parts and elements, and in the details of the construction, as set forth and claimed.

In the drawings:

Fig. 1 is a vertical section of a furnace having the invention attached thereto, showing parts broken away;

Fig. 2 is an elevational view of the fire pot with parts broken away;

Fig. 3 is a section taken on a line corresponding to 3—3 in Fig. 1; and

Fig. 4 is a side elevation of the collar.

In the preferred construction of the invention I provide the furnace 1 comprising the usual casing 2 suitably secured to the front 2' which is suitably fixed to the usual steel drum 3 contained within the casing.

Inside the drum 3 is the inner lining 4 comprising the adjoining firebricks 5 having their outer sides 5' in contact with the drum, whereby the usual fire pot 6 is formed.

The usual door 7 is hingedly connected with the front 2' of the drum to close the aligned opening 8 through the drum 3 and the front 2', through which fuel, as coal, is inserted by manual or mechanical means into the combustion chamber. The usual grate 9 is suitably attached to the drum 3 for the usual purpose of retaining the fuel within the fire pot 6. The main air inlet 3', through the front 2', permits air to pass through the grate into the fire pot when the

door 2'', suitably hinged to the lower end

11 of the front, is open. It is apparent that the various parts previously described may be constructed in any manner, or of any material, suitable for the intended purposes and uses.

Formed in the outer side of the inner lining 4, adjacent its lower edge 12, are the spaced apart circumferential grooves 13 and 14. Intersecting the grooves 13 and 14 are the spaced apart vertical grooves 15, formed in the outer surface of the inner lining, whereby the heated air warmed by the fire in the combustion chamber is adapted to circulate in the grooves 13, 14 and 15. The openings 16 and 16', respectively, in the front 2' and the drum 3, permit air to be received in the grooves 13, 14 and 15. A door 3'' is suitably hinged to the front whereby, when desirable, the openings 16 and 16' may be closed.

Bolted to the outer side 17 of the drum 3 is the pipe 18 having its opening 19 registering with the hole 20 in the drum 3. The hole 20 communicates with the groove 13 in the inner lining.

The right angle elbow 21 in the pipe 18 permits the upper end 22 of the pipe to extend parallel with the adjacent side 23 of the drum 3. The extreme upper end of the pipe 18 is received in the recess 24 of the collar 25 which is secured to the outer side of the drum 3, as by the bolts 26. The aperture 27 in the collar communicates with the smoke or fire-gas hole or outlet 28 in the drum.

Communicating with the recess 24 is the chamber 29 formed circumferentially of the collar. Communicating with the chamber 29 and the aperture 27, in the collar, are a plurality of spaced apart perforations 30, whereby air received through the opening 16, in the drum 3, is adapted to pass through the grooves 13, 14 and 15, pipe 18, recess 24, chamber 29 and holes 30 into the aperture 27 of the collar whereby heated air is mixed with the smoke and gases that escape from the drum 3 into a suitable smoke pipe 31 suitably connected with the collar 25 and the usual chimney flue 31'.

The smoke pipe or tubular smoke and

burned gas conductor 31, which is adapted to radiate heat, is positioned between the casing 2 and the drum 3 from where heated air is suitably conducted to the rooms requiring heat. The smoke pipe is economically maintained at a relatively high temperature because the admission of heated air into the smoke and gasses passing from the drum 3 to the smoke pipe 31 results in efficient combustion. Under certain circumstances it may be desirable merely to connect a smoke pipe to the outer side of the collar and the chimney flue.

It is, therefore, apparent that I have invented a highly desirable device for the purposes intended and which will permit economical use of various grades of coal or other fuel in hot air furnaces.

While I have chosen to illustrate the form and construction of the invention by the herein drawings and explanations of the same, it is understood that the invention resides in the combination, arrangement of the parts and in the details of the construction, as hereinafter claimed. It is further understood that changes in the precise embodiment of the invention, as disclosed herein, can be made within the scope of what is claimed without departing from the spirit of the invention, as other expedients may readily suggest themselves to the art.

What I claim as new and desire to secure by Letters Patent is:

1. In a furnace, the combination with a casing, a fire drum in said casing and having a fire pot therein, an air inlet in said drum, a smoke outlet in said drum, tubular means for conducting the smoke to the flue, and means connecting said tubular means with said drum at said outlet whereby products of combustion are adapted to flow from said chamber toward said flue, of an inner lining in said drum having a circumferential groove and a vertical groove in its outer side, and means to permit air to flow from said grooves into said second mentioned means.

2. In a furnace, the combination with a casing, a fire drum in said casing and having a fire pot, an air inlet in said drum, a products of combustion outlet in said drum, and means for conducting the products of combustion toward the flue, of an inner lining in said drum having a plurality of grooves therein, and means to convey air from said grooves into said means.

3. In a furnace, the combination with a casing, a fire drum in said casing, a fuel doorway through said casing and said drum, an air inlet in said drum, a products of combustion outlet in said drum, and means for conducting said products of combustion and communicating with said outlet, of an inner lining in said drum, and means to convey air from adjacent the outer side of said drum into said means.

4. In a furnace, the combination with a fire drum having a fire pot and having a smoke and burned gas outlet, an inner lining in said drum, tubular means connected with said outlet, a perforated collar for admitting air in the region of the junction of said parts, and means extending through a side of said drum to convey said air from adjacent said inner lining into said collar. 70

5. In a furnace, the combination with a fire pot having an outlet, smoke receiving means connected with said outlet, means for admitting air in the region of the junction of said parts, and means to convey heated air from adjacent the fire pot to said means 80 whereby heated air is mixed with the burned gas and smoke which escapes from said fire pot through said outlet. 75

6. In a furnace, the combination with a drum having a fire pot and having an outlet, an inner lining in said drum, smoke receiving means connected with said outlet, means for admitting air in the region of the junction of said parts, and a pipe to convey said air from adjacent said inner lining 90 to said means. 85

7. In a furnace, the combination with a drum having a fire pot and having a smoke outlet, an inner lining in said chamber and having a circumferential groove in its outer side, smoke-conducting means connected with said outlet, a perforated collar for admitting air in the region of the junction of said parts, and means to convey said air from said groove to said collar. 95

8. In a furnace, the combination with a drum having a fire pot and having a smoke outlet, smoke receiving means connected with said outlet, means for admitting air in the region of the junction of said parts, and means to convey said air from a heated portion of said drum to said means. 100

9. In a furnace, the combination with a fire pot having a smoke outlet, of an inner lining in said pot, tubular means connected with the chimney flue and said outlet, a collar formed with a circumferential chamber and having a plurality of perforations leading from said chamber into the aperture in said collar and having a recess leading from the outer surface into said chamber, said collar connected to said furnace between said outlet and said tubular means whereby the smoke and gas from said fire pot is adapted to pass through said aperture into said tubular means, and means to convey air from adjacent said inner lining into said recess whereby heated air is mixed with said products of combustion, substantially as and for the purposes specified. 110

10. The combination with a furnace having a fire pot having an upward smoke outlet, of an inner lining in said pot and having a groove therein, tubular means communicating with the chimney flue and said 120 125 130

- outlet, a collar formed with a circumferential chamber and having a plurality of spaced apart perforations therein leading from the chamber into the aperture in said collar, said collar having a recess leading from its outer surface into said chamber and said collar forming communications between said outlet and said tubular means whereby the products of combustion in said 5 furnace are adapted to pass from said fire chamber through said aperture and into said tubular means, and means to convey air from said groove into said recess whereby heated air is mixed with said products of 10 combustion, substantially as and for the purposes specified.
11. In a furnace, the combination with a fire pot having a fire-gas outlet, and tubular means connected with the chimney flue and 15 said outlet, of a collar formed with a circumferential chamber and having a perforation leading from said chamber into the aperture in said collar and having a recess leading from the outer surface into said 20 chamber, and said collar connected to said furnace between said outlet and said tubular means whereby air is adapted to be admitted into the products of combustion which passes from said fire pot through said aperture 25 into said tubular means.
12. In a furnace, the combination with a casing, a fire drum in said casing, a fuel doorway extending through said drum, an air inlet in said drum, a products of combustion outlet in said drum, and tubular means for conducting said products of combustion and communicating with said outlet, of an inner lining in said drum and having a groove therein, and means to 30 convey air from said groove into said tubular means.
13. In a furnace, the combination with a fire pot having an outlet, and means connected with the chimney flue and said outlet, of a collar formed with a circumferential chamber and having a perforation leading from said chamber into the aperture in said collar and having a recess leading from the outer surface into said chamber, said 35 collar connected to said furnace between said outlet and said first mentioned means whereby products of combustion are adapted to pass from said fire pot through said aperture into said first mentioned means, and means to convey air from adjacent said fire pot into said recess whereby heated air is mixed with said products of combustion, substantially as and for the purposes specified.
- 40 14. In a furnace, the combination with a fire pot having an upper outlet, of an inner lining in said pot and having a vertical groove and a circumferential groove in its outer side adjacent the lower portion of said 45 fire pot, means connected with the flue and
- said outlet, a collar formed with a circumferential chamber and having a plurality of perforations leading from the chamber to the aperture in said collar and having a recess leading from its outer surface into said chamber and said collar connected between said outlet and said first mentioned means whereby the products of combustion are adapted to pass from said fire pot through said aperture and into said first 50 mentioned means, and means to convey air from said groove into said recess whereby heated air is mixed with said smoke and gas previous to its entering the first mentioned means, substantially as and for the 55 purposes specified.
15. In a furnace, the combination with a casing, a fire drum in said casing and having a fire pot, an air inlet in said drum leading into said pot, an outlet in said drum leading from said chamber, air admission means communicating with said outlet, of an inner lining in said drum having a groove therein, and means to convey air from said 60 groove into said air admission means.
16. The combination with a furnace having a fire pot having an upper smoke outlet, means communicating with the chimney flue and said outlet, a collar formed with a circumferential chamber and having a 65 plurality of spaced apart perforations therein leading from the chamber into the aperture in said collar, said collar having a recess leading from its outer surface into said chamber whereby air is received in the 70 aperture from said recess, and said collar forming communications between said outlet and said first mentioned means whereby the products of combustion are adapted to be mixed with air as it passes from said fire pot through said aperture and into said 75 first mentioned means.
17. The combination with a furnace having a fire pot having an upper fire-gas outlet, a collar formed with a circumferential 80 chamber and having a plurality of spaced apart perforations therein leading from the chamber into the aperture in said collar, said collar having a recess leading from its outer surface into said chamber whereby air is received in the aperture from said 85 recess, and said collar forming communications between said outlet and the flue whereby the products of combustion are adapted to be mixed with air as it passes from the 90 said fire pot through said aperture.
- JAMES ELIPHAS WITTE.
